UNITED STATES PATENT OFFICE.

NAPOLEON DU BRUL, OF CINCINNATI, OHIO.

DESIGN FOR A CIGAR-WRAPPER-CUTTER GAGE.

SPECIFICATION forming part of Design No. 35,205, dated October 22, 1901.

Application filed September 11, 1901. Serial No. 75,105. Term of patent 14 years.

To all whom it may concern:

Be it known that I, NAPOLEON DU BRUL, a citizen of the United States, and a resident of Cincinnati, in the county of Hamilton and State of Ohio, have invented and produced a new and original Design for a Cigar-Wrapper-Cutter Gage, of which the following is a full, clear, and exact specification.

My new design is illustrated in the accompanying drawings, in which—

Figure 1 is a plan view; Fig. 2, a section from front to rear on the line A B, Fig. 1; and Fig. 3, a section on the line C D, Fig. 1.

As shown in the drawings, my design comprises an approximately oval open frame having a vertical rectangular flange, rearwardly-

projecting arms of oval section, a connecting-bar of oval section at the rear ends of the arms, and perforated cylindrical bosses at the intersections of the connecting-arm with said rearwardly-projecting arms.

Having thus described my new design, what I claim as new, and desire to secure by Letters Patent, is—

The design for a cigar-wrapper-cutter gage, substantially as herein shown and described.

The foregoing specification signed this 12th day of August, 1901.

NAPOLEON DU BRUL.

In presence of—

W. M. BEINHART,
HARRY WHYRICH.
